ATTORNEY

BY

UNITED STATES PATENT OFFICE.

HARRY W. DARR, OF JOHNSTOWN, PENNSYLVANIA.

LOCK-PROTECTOR.

1,372,008.

Specification of Letters Patent. Patented Mar. 22, 1921.

Application filed February 21, 1920. Serial No. 360,349.

To all whom it may concern:

Be it known that I, HARRY W. DARR, a citizen of the United States, residing in the city of Johnstown, in the county of Cambria and State of Pennsylvania, have invented certain new and useful Improvements in Lock-Protectors; and I do hereby declare the following to be a full, clear, and exact description, such as will enable others skilled in the art to which it appertains to make and use the same.

My invention relates to a lock protector which is particularly adapted for use in locking the doors of cupboards and store-
rooms and similar doors which are intended to provide quick access to supplies contained in said cupboard, storeroom, etc., by any one in case of emergency irrespective of whether the key, which is ordinarily kept in a con-
venient location, can be had or not.

My lock protector is especially useful in connection with cupboards containing surgical supplies for emergency use around manufacturing establishments, such supplies consisting of plasters, bandages, medicaments, stretchers, blankets, etc. Heretofore it has been customary to leave these doors unlocked, so that in case of emergency any one could obtain immediate access to the supplies in order to treat an injured person by first aid, but unfortunately unscrupulous persons have taken advantage of this fact and have helped themselves to these supplies to such an extent that it is frequently discovered that when such supplies are needed in an emergency they are not to be found.

My invention consists in a certain improved form of lock, preferably a spring lock similar to a night latch, the bolt of which extends a sufficient distance beyond the lock to expose said bolt which is provided with a convenient notch or projection in or against which the end of a finger, pencil, stick, etc., can be placed for retracting the same, this locking bolt being guided on all sides to maintain its axial movement, and this is then covered with a piece of glass or other frangible material, preferably set in a frame, the outer part of which is open with the end of the glass abutting against the door jamb in such a way that the glass cannot be removed when the door is shut. In case of an emergency when

some one desires access to the cupboard, the 55 glass can be quickly broken with a hammer or other convenient instrument, a finger, pencil, or stick inserted in the notch or against the projection, the spring bolt pushed back and the door opened. After 60 this is done, it is reported to the person in charge of the cupboard and the key, and he can replace the glass with a new one by merely sliding it in position when the door is open, and when the door is closed the 65 glass is held by the jamb, so that it cannot be withdrawn to obtain surreptitious access to the cupboard.

Having thus given a general description of my invention, I will now, in order to 70 make the matter more clear, refer to the annexed sheet of drawings which forms part of this specification and in which like characters of reference refer to like parts:—

Figure 1 is a front elevation of my im- 75 proved lock protector attached to a portion of a door and showing the adjacent part of the door jamb; Fig. 2 is a horizontal central longitudinal sectional plan of Fig. 1, the lock being shown in plan; Fig. 3 is a 80 front elevation similar to Fig. 1 of a slightly modified form of my lock protector; Fig. 4 is a central longitudinal sectional eleva- 85 tion of the modification illustrated in Fig. 3; and Figs. 5 and 6 are details of other slight modifications of my spring pressed locking bolts.

Referring now to the characters of reference on the drawings:—1 indicates a portion of the door, 2 the door jamb thereof, 3 the 90 recess in the door jamb to receive the end of the bolt, 4 is the lock plate on the door jamb and is preferably made of metal. Referring now to Figs. 1 and 2, 5 is the lock which may be of the spring latch type, the 95 interior details of which may be of any desired form; 6 is the inner flange of the lock which is secured to the inside of the door as illustrated, 7 is the key-hole, 8 is the casing or frame work for my glass protector, pro- 100 vided with a groove 9 therein to receive the edges of the glass 10. The lock bolt is 11.

In all the figures the finger notch in the bolt is 12, and although I have shown this notch 12 in the lock bolt for the purpose of 105 inserting a finger or instrument therein to move the same, this may be either a notch or a projection, as desired.

In Figs. 3 and 4 the lock 14 is provided with a flange 13 whereby it is secured to the inside of the door. The keyhole is 15, and the lockbolt 22 is provided with a slot 16 and an auxiliary lock bolt 17 adapted to move relative to the main lockbolt 22 but normally pressed outward by the spring 18. The style of construction shown in Figs. 3, 4, 5 and 6 is adapted to be used in connection with a positive locking bolt and the spring attachment is made between the auxiliary lock bolt and the main lock bolt, as illustrated.

Referring now to Figs. 3 and 4, the auxiliary lock bolt 17 is provided with a notch 19 adapted to receive the spring 18 and also has a portion of its end cut away as illustrated at 20. 21 is a set screw passing through the slot 16 in the main lock bolt 22 and engaging the inner end of the auxiliary lock bolt 17, and is thus adapted to serve as a slide and stop for the movement of the auxiliary lock bolt 17.

Referring now to Fig. 5, the main lock bolt 23 is provided with a notch or cut out portion 24 and a slot 25 to receive the end of the leaf spring 31, as illustrated. The notch 25 has a further enlargement 26, the end of which serves as a stop to limit the backward movement of the auxiliary lock bolt 28, and the lock bolt 23 has a projecting end 27 to serve as a limit or stop for the forward movement of the auxiliary lock bolt 28. The auxiliary lock bolt 28 has a notch 29 and projecting end 30, as illustrated, to coöperate with the other portions.

Referring now to Fig. 6, the auxiliary lock bolt is 32, having a projecting end portion 33. The lock bolt 34 has a projecting end portion 35 to coöperate with the other portions, and a helical spring 36 is inserted between the end of the auxiliary bolt and a portion of the lock bolt 34, so that the auxiliary bolt may move relatively to the other lock bolt. These bolts have notched or cut out portions 37 and 38 respectively.

Although I have described and illustrated my invention in considerable detail, I do not wish to be limited to the exact and specific details thereof, as shown and described, but may use such modifications in, substitutions for, or equivalents thereof, as are embraced within the scope of my invention, or as pointed out in the claims.

Having thus described my invention, what I claim and desire to secure by Letters Patent is:—

1. In combination with a door, a lock mounted thereon and provided with a spring pressed bolt extending outwardly therefrom, grooves in the body of said lock, a frangible cover slidably mounted in said grooves and over said bolt and retained in place by the door jamb when the door is closed, and a finger notch in said bolt under said cover. 65

2. The combination with a door lock provided with an outwardly extending spring pressed bolt, of grooves in the body of said lock, a frangible cover slidably mounted in said grooves and over said bolt and adapted 70 to be held in place by the door jamb when the door is closed, and a finger notch in said bolt under said cover.

3. A lock provided with an outwardly extending spring pressed bolt having a finger 75 notch therein, grooves in the body of said lock, a frangible cover removably secured over said bolt and having the side and inner edges slidably mounted in said grooves and the outer edge free, said cover being thereby 80 adapted to be held in place by the door jamb when the door is closed.

4. A lock provided with a comparatively long, spring pressed bolt extending outwardly therefrom, grooves in the body of 85 said lock, a frangible cover slidably mounted and normally retained in said grooves and over said bolt, whereby upon breaking said cover access may be had to a finger notch in said bolt for retracting the same. 90

5. A lock provided with a spring pressed bolt extending therefrom a distance greater than the length of the engaging end thereof, grooves in the body of said lock, a notch in said bolt, and a frangible cover slidably mounted over the same in said grooves. 95

6. A lock provided with a spring pressed bolt extending outwardly a considerable distance therefrom and provided with means for engaging the same, grooves in the body 100 of said lock, and a frangible cover slidably mounted and normally retained in said grooves and over said bolt, whereby access can be had for retracting the same in the absence of the key. 105

In witness whereof I hereunto affix my signature.

HARRY W. DARR.
